REFUSE VEHICLE

Mario Micheluzzi fu Leopoldo, Trieste, Italy

Application May 22, 1936, Serial No. 81,212
In Italy May 25, 1935

1 Claim. (Cl. 214—67)

This invention relates to the transportation of refuse and has for its object to provide an arrangement whereby the refuse is collected and conveyed in a highly hygienic manner.

5 According to the invention, refuse bins are manually conveyed to a refuse vehicle provided with members depending from the side of said vehicle, on to which the refuse bins are connected, and means are associated with the refuse vehicle, 10 whereby the refuse bins are elevated, inverted over an opening in the refuse vehicle, said opening being provided with a removable cover, which latter opens simultaneously with the movement of the refuse bins, whereby the refuse is caused to 15 fall on to a conveyer arranged in the refuse vehicle so that, the refuse will be distributed evenly in said vehicle.

After the refuse bin has been emptied, the 20 sequence of operations as herein set forth is reversed, and when the mechanism on the refuse vehicle is again at its normal position, the refuse bins are then removed from the members.

The invention will now be described with reference to the accompanying drawing, in which:—

25 Figs. 1 and 2 are perspective views of the mechanism used for elevating and emptying the refuse from the refuse bin into the refuse vehicle, and, Fig. 3 is a side view partly in section of a part of the refuse vehicle.

30 A pinion 1 fixed on to the end of a horizontal shaft 2 rotatably mounted in the refuse vehicle 40 engages with a pinion 3 which is driven from the driving shaft 41 of the motor by means of pulleys 6 and 7 as shown in Figs. 2 and 3.

35 A crank arm 4 is fixed to an axle 27 which in turn is connected to two curved levers 21 Fig. 1 provided with an arm 22 carrying a counter-weight 17. The levers 21 are articulated to an arm 15 to which the refuse bin 16 is connected by 40 means of trunnions 18 engaging bayonet slots as shown in Fig. 1.

A conveyer 10 with blades 26 is arranged within a cylinder 11 provided with inwardly extending fins 19, whereby the refuse on being emptied automatically into the vehicle is transported along

the conveyer 10 and finally discharged into the vehicle container 40.

Figs. 2 and 3 show forms of producing the oscillating movement of the crank arm 4. The link 5¹ is articulated at 6¹ to the disc 6¹¹ of the pinion 1 5 on the end of the conveyer shaft 2.

After the refuse bin has been placed in position, the main driving shaft 41 is then driven from the motor vehicle causing the bin to be raised its contents tipped into the vehicle container 40, and then lowered and manually removed. When the refuse bin is elevated the closure 18 to the opening to the refuse vehicle moves between guides 14 by means of an arm 20 integral with a lever 21. If desired the said closure may 15 consist of textile or like material.

When the refuse vehicle is full, it can be tipped, and after the refuse is discharged, the container is swung back to its normal position.

By this invention the refuse is collected and 20 transported without exposure to the surrounding atmosphere.

I claim:

A refuse vehicle comprising a refuse container with an opening in the top, a slidable cover fitted 25 to said container for closing the opening therein, a short cylinder provided with radial guides and a peripheral opening mounted longitudinally in said container, the peripheral opening in alignment with the opening in said container, a short 30 screw conveyer rotatably mounted within said cylinder, a pair of articulated levers pivotally mounted on said container, and means for imparting oscillating movement to said levers whereby, said levers on moving in one direction 35 elevate a refuse bin, move said cover off the opening in the container so that the refuse can be automatically discharged through the opening in said container and cylinder respectively on to the screw conveyer and radial guides of said cylinder, 40 directed into the container, and on the reverse movement automatically slide the cover over the opening in said container and lower the refuse bin.
